ATTORNEY

UNITED STATES PATENT OFFICE.

SAMUEL GOLDBERG, OF DORCHESTER, MASSACHUSETTS.

HAIR CURLER.

Application filed January 2, 1926. Serial No. 78,975.

This invention relates to hair curling devices and the object of the invention is to provide a new and improved curler which is designed to produce a wave that is known as a Marcel wave.

Another object of my invention is to produce a device upon which the hair may easily and conveniently be wound, and which will hold the hair thereon in a tightly wound position.

Another object of my invention is to produce a device on which the hair may be coiled either towards the scalp or away from it.

15 The invention will be hereinafter considered in detail and specifically claimed. Reference will now be had to the drawing forming a part of this application, wherein there is illustrated a preferred embodiment of my 20 invention, but it is understood that the elements thereof can be varied or changed as for shape, size or form without departing from the spirit of the invention.

In the drawings:—

25 Fig. 1 is a view of the curler when it is open.

Fig. 2 is a view of the curler when closed.

Fig. 3 is a sectional view on line 3—3.

30 1 denotes a circular rod whose diameter decreases from the two ends to a minimum at the centre as shown in Fig. 1. A semi-cylindrical lock 4 is pivotally attached to the rod and is shaped to conform to the rod 1, so as to engage and hold securely the ends 35 of a lock of hair. To one end of the rod there is attached a flat metallic plate 5 which is bent somewhat upward at the opposite end. This end fits into an opening 6 which will now be described.

40 One end of the rod 1 fits rotatably and tightly into a hollow cylinder 7, provided

with an opening or slit 8. The rod is provided with a pin 9 which fits into the slit 8 and keeps the cylinder securely on rod 1. The end of the flat plate 5 fits into the opening 6 which is produced by the hollow cylinder and rod 1 as shown in Fig. 3. The opening 6 is large where the end of plate 5 enters it. As the cylinder 7 is rotated to more securely engage the end of plate 5, the opening becomes narrower and thus presses the plate 5 down, holding the hair tightly in position.

The ends of the hair are first engaged at the centre of rod 1 by means of lock 4, wound around the rod 1 and held securely there by flat plate 5.

Another method is to start winding the hair on rod 1 and then gradually going to the other end.

Having described my invention, what I claim is:—

1. A device of the class described comprising a curler formed of a rod whose centre is of a smaller diameter than the ends, a locking device for the ends of the hair, a flat plate to hold the curled hair in place and means to hold the flat plate securely in place.

2. A curler comprising a rod of cylindrical cross section tapering from both ends to the center thereof, a lock for the ends of the hair secured to said rod, and a holding device for the curled hair secured to said rod.

3. A curler comprising a rod of cylindrical cross section tapering from both ends to the center thereof, a lock for the ends of the hair secured to said rod, a holding device for the curled hair secured to said rod, and a rotatable clamp for securing said holding device in place.

SAMUEL GOLDBERG.
